UNITED STATES PATENT OFFICE.

RUDOLPH HOFFMAN, OF KANKAKEE, ILLINOIS, ASSIGNOR TO SEARS, ROEBUCK AND CO.,
OF CHICAGO, ILLINOIS, A CORPORATION OF NEW YORK.

WICK STRAIGHTENER FOR OIL HEATERS.

Application filed July 12, 1920. Serial No. 395,486.

To all whom it may concern:

Be it known that I, RUDOLPH HOFFMAN, a citizen of the United States, residing at Kankakee, in the county of Kankakee and 5 State of Illinois, have invented certain new and useful Improvements in Wick Straighteners for Oil Heaters, of which the following is a specification.

The invention relates in general to oil 10 heaters of the type comprising a reservoir or font, and a burner having a pair of concentric wick tubes one of which depends into the font and guides a wick surrounding the same for up and down movement by suitable 15 raising and lowering means. Wicks employed in heaters of the character referred to are severed at diametrically opposite points, near their lower ends, so as to permit of the spreading of the lower end portion of the wick over the bottom of the reservoir around the inner wick tube. When 20 the wick is new and of substantial length, a considerable portion thereof is flared outwardly over the bottom of the reservoir, and 25 after the heater has been in use for some time, the tendency of the outwardly flared portion of the wick is to become set so as to retain its outwardly flared form. The result is that as the wick is gradually consumed 30 in use so that it becomes necessary from time to time to elevate it with reference to the bottom of the reservoir, the outwardly flared portion of the wick is carried a substantial distance above the bottom of the reservoir; 35 hence, the heater is operative only when the supply of oil in the reservoir is maintained relatively high.

The present invention has for its object 40 the provision of wick straightening means of simple construction and yet of an efficient character adapted to maintain the lower end portion of the wick at all times as near the bottom of the reservoir and around the lower portion of the wick tube as the length 45 of the wick will permit. Thus, when a substantial portion of the wick has been consumed, necessitating its elevation in the wick tubes, the lower end portion will be straightened out so as to be immersed in 50 the oil contained in the reservoir.

In the drawings, Figure 1 illustrates the invention as applied to an oil heater of a well known form, the view being a fragmentary central vertical section. Fig. 2 is a 55 side elevation of the wick straightening

means showing diagrammatically the manner of applying it to the wick.

The heater comprises generally a reservoir or font 3 having associated therewith a burner 4 comprising inner and outer wick tubes 5 and 6 having an annular or cylindrical wick 7 therebetween. Said wick tubes serve to guide the wick as it is raised and lowered by suitable means including a toothed wheel 8 coacting with a perforated sleeve fixed to the wick and constituting a carrier 9. 10 designates generally a flame spreader having means 11 for limiting the upward movement of the wick with reference to the wick tubes 5 and 6. The inner wick tube 5 depends to the bottom of the font 3, the latter being apertured and flanged upwardly as at 12 to receive the lower end of said wick tube which is secured therein as by means of solder to form 75 a liquid-tight joint.

The lower end portion of the wick is usually divided or split at diametrically opposite sides to form gaps 13 to permit of the outward flaring of the lower end portion of the wick over a downwardly and outwardly inclined supporting or bracing ring 14 for the inner wick tube. This ring is secured at its inner and outer edges to the inner wick tube and the bottom of the 85 font respectively.

The wick straightener, as constructed in accordance with the present invention, is in the form of a single helically coiled wire 15 constituting a coiled spring adapted to 90 receive or surround the lower end portion of the wick and having its opposite ends removably secured to the wick carrier a substantial distance above its lower end and at the lower end respectively. For the purpose of thus securing the member 15, the upper end of the member is provided with an upwardly projecting finger 16 bent so as to be capable of being inserted through one of the apertures of the wick carrier 9 with the 95 free end of the finger projecting outwardly through an adjacent aperture; and the lower end of the member 15 may be provided with one or more hooks 17 adapted to engage in the wick. 100

As shown in Fig. 1, the member 15 flares outwardly slightly at its lower end over the top of the conical ring 14 and thereby effectively serves to maintain the lower end of the wick in proper relation to the bottom of 110

the reservoir except as limited by its length. The wick thereby remains at all times immersed in the oil.

It will be seen that I have provided a device of an extremely simple character for efficiently accomplishing a desirable result. After a wick has been so far consumed in use as to necessitate its replacement by a new wick, the straightening member may be 10 quickly and easily detached and applied to the new wick.

I claim as my invention:—

1. In combination with an oil reservoir, a burner having a wick tube depending into 15 the reservoir, and an annular wick surrounding said wick tube; straightening means for the lower end portion of the wick comprising a helically coiled member surrounding the lower end portion of the wick and re- 20 movably secured thereto, said means being operable yieldingly to maintain the lower end of the wick near the bottom of the reservoir.

2. The combination with an oil reservoir, 25 a burner having a wick tube depending into the reservoir, and an annular wick surrounding said tube and having its lower end adapted to flare outwardly over the bottom of the reservoir; of means tending to move 30 the lower end portion of the wick toward the bottom of the reservoir including a member in the form of a helically coiled wire spring surrounding the wick and removably secured thereto.

3. The combination with a reservoir, a burner having a wick tube depending into the reservoir, and a wick surrounding the tube and having its lower portion adapted 40 to assume an outwardly flared form over the bottom portion of the reservoir; of means tending to maintain the lower end portion of the wick near the bottom of the reservoir comprising a resilient straightening member in the form of a coil surround- 45 ing the wick and secured at a point in fixed relation thereto.

4. The combination with a reservoir, a burner, and a wick depending into the reservoir and having its lower portion severed 50 to permit of its flaring outwardly over the bottom of the reservoir; of straightening means for the wick comprising a helically coiled member adapted to surround the wick and to engage with the wick near the lower 55 end thereof and at a point spaced a substantial distance above its lower end.

5. In combination with a reservoir, and a burner having an annular wick depending into the reservoir, said wick being severed in its lower end portion so as to permit it 60 to flare outwardly over the bottom of the reservoir; a straightening means for the outwardly flared portion of the wick comprising a single member carried by the wick and surrounding it, said member having at 65 its upper end a finger adapted to be secured at a point in fixed relation to the wick a substantial distance above its lower end, and at its lower end a hook adapted to engage with the lower end of the wick. 70

6. In combination with a reservoir, and a burner having an annular wick depending into the reservoir and severed in its lower portion so as to permit it to flare outwardly over the bottom of the reservoir, said 75 wick having a metallic perforated carrier; straightening means for the lower end portion of the wick comprising a single helically coiled member adapted to surround the wick and having at its upper end a finger 80 for engaging in one of the apertures of the carrier and at its lower end a hook for engaging in the lower end of the wick.

7. The combination with a reservoir and a burner having an annular wick depending 85 into the reservoir, of yielding means surrounding the wick and carried entirely independently of the reservoir and secured at its ends in fixed relation to the wick, said means being operable to maintain the lower 90 end portion of the wick near the bottom of the reservoir except as limited by the length of the wick.

8. The combination with a reservoir and a burner having an annular wick depending 95 into the reservoir, of a single helically coiled spring surrounding the wick having its lower extremity flared outwardly to maintain the lower end portion of the wick near the bottom of the reservoir. 100

9. A straightening means for tubular wicks of oil heaters comprising a member in the form of a helix adapted to surround the wick and operatively engaging therewith at its ends in fixed relation to the wick 105 so as to tend to move the lower end portion of the wick downwardly toward the bottom of the reservoir of the heater.

In testimony whereof, I have hereunto set my hand.

RUDOLPH HOFFMAN.
